UNITED STATES PATENT OFFICE.

JAMES BUCKLER, OF WORCESTER, MASSACHUSETTS.

LOOM FOR WEAVING PILE FABRICS.

SPECIFICATION forming part of Letters Patent No. 747,587, dated December 22, 1903.

Application filed April 27, 1903. Serial No. 154,445. (No model.)

To all whom it may concern:

Be it known that I, JAMES BUCKLER, a citizen of the United States, residing at Worcester, in the county of Worcester and State of Massachusetts, have invented certain new and useful Improvements in Looms for Weaving Pile Fabrics, of which the following is a specification.

My invention relates to looms for weaving pile fabrics, and more particularly to the class of looms shown and described in my United States Letters Patents No. 576,300, dated February 2, 1897, and No. 672,393, dated April 16, 1901, in which looms the formation of the pile-loops is effected upon longitudinal wires, which extend in the direction of the length of the warp-threads.

The object of my invention is to improve upon the construction of the class of looms referred to as now ordinarily made.

In my improved construction there is no transverse movement of the frames or heddles which carry the pile-warps and support the pile-wires which form the loops; but the pile-warps are carried over the pile-wires by a device or mechanism which extends transversely across the loom and has a transverse reciprocating movement communicated thereto at regular intervals. The pile-warps are carried up at the proper time above the pile-wires and moved over the same to form the loops, and, further, in my improvements I arrange the pile-wires in two planes at their attached ends to form two sets or series in two different horizontal planes. I also make the heddles which carry the blades with the pile-wires attached to their upper ends with bends or offsets therein, so arranged relatively to each other that there will be a free and open space on each side of the upper end of the blade to which the pile-wire is attached, thus permitting of the pile-warp passing freely down on one side or the other of the upper end of the blade and of the pile-wire attached thereto without liability of being caught on the blade or passing down on the wrong side of the blade during the formation of the shed, and, further, in my improvements I preferably provide mechanism connected with the cords or heddles of the pile-warps and means for operating said mechanism at regular in-

tervals, so that all the pile-warps which are in the upper or lower plane of the shed will be carried up or raised at regular intervals, or after a certain number of picks of filling, 55 above the blades to which are attached the pile-wires, and caused to move into their proper position on the formation of the shed, and not to interfere with the proper movement and position of the pile-warps which are 60 carried across the pile-wires.

I have only shown in the drawings sufficient portions of a loom of the class referred to with my improvements applied thereto to enable those skilled in the art to which my 65 invention belongs to understand the construction and operation of the same.

Referring to the drawings, Figure 1 is a front view of portions of a loom with my improvements applied thereto looking in the direction of arrow *a*, Fig. 2, taken at a point indicated by line 1 1, same figure. Fig. 2 is a sectional elevation of the parts shown in Fig. 1, taken at a point indicated by line 2 2, Fig. 1, looking in the direction of arrow *b*, 75 same figure. The lay, breast-beam, and take-up roll are shown in this figure. Fig. 3 is a diagrammatic view showing a different position of the harness-frames in the formation of the shed from what is shown in Fig. 2. 80 Fig. 4 corresponds to Fig. 3, but shows a different position of the harness-frames. Fig. 5 is a front view, on a smaller scale, of the lifting-bar for the pile-warp threads and mechanism for operating the same, taken at 85 a point indicated by lines 5 5, Fig. 6, looking in the direction of arrow *c*, same figure. Fig. 6 is a sectional elevation on line 6 6, Fig. 5, looking in the direction of arrow *d*, same figure. The lay, breast-beam, and take-up roll 90 are shown in this figure. Fig. 7 is, on a much-enlarged scale, a perspective view of three of the heddles, their attached blades, and the pile-wires for the pile-loops. The broken lines show a different position of one 95 of the pile-wires. Fig. 8 corresponds to Fig. 2, but shows a different position of the harness-frames and the lay and also shows a modified construction of the pile-wires and of the heddles carrying the same and of the reciprocating device for moving the pile-warps transversely, said heddles being movable ver-

tically, and also the reciprocating device. The lifting-bar is not shown in this figure, and Fig. 9 shows a modified construction of the device for moving the pile-warps trans-

versely across the pile-wires.

In the accompanying drawings, 1 is a portion of a loom side or frame. 2 is the breast-beam; 3, the take-up roll for the woven fabric 3', and 4 the lay-sword; 5, the lay; 6, the hand-rail, and 7 the reed. In this instance there are three harness-frames 8, 9, and 10, provided with heddles 8', 9', and 10', which carry two binder-warps 11 and 12 and the stuffer-warp 13 and have a vertical motion in the usual way to raise and lower the warps and form the sheds. The heddles 14, which support the blades which carry the pile-wires 15, do not have a transverse movement and are preferably stationary and are attached at their upper ends, in this instance by cords 16, to a transverse bar 17, secured at its end to lugs 18 on stands 19 on the loom-frame. (See Fig. 1.) The lower ends of the heddles 14 preferably extend loosely through openings in a transverse bar 20, which is secured at its ends to stands 21 on the loom-frame 1 and have attached thereto by cords 22 weights 23.

Each heddle 14, which is preferably made of flat metal, has a bend or offset 14' therein near its central longitudinal portion, and the bends or offsets 14' are so arranged relatively to each other as to form open or clear spaces on each side of the upper end of each blade 24, which is preferably made separate from and secured at its lower end to the heddle 14 and has secured to its upper end, which is preferably bent over to form a loop, the inner end of the pile-wire 15. (See Fig. 7.)

40 The blades 24 are preferably of two different lengths. The shorter ones extend at their upper ends in one horizontal plane, and the longer ones extend in another horizontal plane, forming two sets or series with the long and short blades arranged alternately.

45 The pile-wires 15 are preferably made of flat metal, tapering toward their free ends, and may be pivotally connected with the upper ends of the blades 24. In this instance they extend into the loops 24' and are secured therein by pivot-pins 26 to have a pivotal motion in a vertical plane, as shown by broken lines in Fig. 7. The extreme pointed end 15' of each pile-wire 15 may be made 50 separate from and pivoted to the main portion of the wire at 15' to have an independent vertical movement. (See Fig. 7.)

Instead of making the pile-wires 15 of flat metal, as shown in Fig. 7, they may be made 60 of round flexible wire, as shown at 15' in Fig. 8, and pivotally attached to the upper ends of the blades 24.

65 By reason of the upper ends of the blades 24 extending in two different planes the attached ends of the pile-wires 15 will also extend in two different planes one above the other. The advantage of this is that there

is more space for the pile-warps to work in, and they will not be liable to catch on the upper ends of the blades 24 or pass down on the wrong side of said blades.

To carry the pile-warps over the pile-wires 15 first on one side and then on the other in the formation of the loops, I preferably use a reciprocating comb 27, having a transverse 75 motion in the direction of the width of the fabric and supported in proper position just back of the heddles 14, in this instance on crank-arms 28 and 29, which are fast on vertically-extending and rocking shafts 30 and 31, having bearings in stands 32 and 21. To one of the rock-shafts, as 30, is secured a crank-arm 33, to which through intermediate connections (not shown) to some driven part of the loom is communicated a movement at 85 regular intervals to rock or rotate the shaft 30 and communicate at regular intervals a transverse reciprocating movement to the comb 27, between the teeth 27' of which the pile-warps 34 are carried up at the proper 90 time and carried over the adjoining pile-wires by the transverse movement of said comb 27. The lower ends of the teeth 27' of the comb 27 extend down a little below the upper ends of the lower series of blades 24. 95

Instead of the comb device above described and shown in the drawings any other suitable device for moving the pile-warps transversely over the pile-wires to form the loops may be employed—for example, the device 100 shown in Fig. 9, which consists of a series of levers 50, pivoted at 51 on a stationary bar 52, with their lower ends extending down below the upper ends of the blades 24 and their upper ends pivoted to a transversely-moving 105 bar 53, having a reciprocating movement corresponding to the movement of the comb 27.

In connection with my improvements above described I preferably use mechanism connected with the cords or heddles of the pile-warps and means for operating said mechanism at regular intervals or after a certain number of picks of filling to cause all of the pile-warps which are in the upper or lower plane of the shed to be raised or carried up 115 above the upper ends of the blades to which are attached the pile-wires. In this instance I have shown in the drawings a vertically-moving bar 35, having a series of holes therein through which extend the cords 36, which 120 form the heddle-cords for the pile-warps 34. Said cords have weights 36' on their lower ends and have knots therein to engage the vertically-moving bar 35. A vertical motion is communicated to the bar 35 to raise said bar to its highest position and with it all of the cords 36, carrying the pile-warps at regular intervals, in this instance by means of chains 38 and links 39, connected to crank-arms 40 on the rock-shaft 41, supported in 125 bearings 42 on the upper ends of the loom-frame 1. On one end of the rock-shaft 41 is fast a crank-arm 43, to which is secured the upper end of the connector 44. The lower

end of said connector 44 is pivotally attached to a lever 45, pivoted at its other end on a stand 46 and having an extension 45', with a roll thereon, to travel in a cam-groove 47' in the cam 47, fast on a shaft 48, mounted in bearings on the stand 46, said shaft being driven from some driven part of the loom. The ends of the vertically-moving bar 35 in this instance are provided with plates 35', which extend into a vertical slot in the stand 19, secured to the loom-frame 1. In the formation of the sheds in the operation of weaving when the lifting-bar 35 is in its lowest position the pile-warps 34 connected therewith are carried to the lower plane of the shed, as shown in Fig. 4, preparatory to the throwing of the shuttle and the beating up of the lay. When the lifting-bar 35 is in its intermediate or middle position, the pile-warps 20 34 are carried to the upper plane of the shed, as shown in Fig. 3, preparatory to the throwing of the shuttle and the beating up of the lay. When the lifting-bar 35 is in its highest position, as shown in Fig. 2, then the pile-warps 25 34 are carried up between the teeth 27' of the comb 27, as shown in Fig. 2, so that the transverse movement of the comb will carry all of the pile-warps in one direction or the other over the pile-wires, according to the direction of movement of the comb. The raising of the lifting-bar 35 at regular intervals to its highest position will carry up all of the pile-warps 34 above the upper ends 30 of the blades 24 and between the teeth of the comb 27 and will insure the proper position and movement of the pile-warps in the formation of the shed.

In Fig. 8 is shown a modified construction of the bar 17, which carries the heddles, to 40 which are attached the blades and the pile-wires. In said figure the transverse bar 17, which supports the heddles 14, has a reciprocating vertical motion to carry the attached ends of the wires 15^a, preferably made of flexible wire, above and below the horizontal plane of the woven fabric, as shown by full and broken lines in said figure. The transversely-moving comb 27 also has a corresponding reciprocating vertical motion, as shown by full 45 and broken lines in Fig. 8.

Any suitable means may be employed to raise and lower the bar 17, carrying the heddles 14, at regular intervals and also raise and lower the transversely-moving comb 27.

5 In the drawings I have shown the several parts of the loom adapted for plain weaving and only one set of pile-warps 34, all of which are connected to the vertically-moving lifting-bar 35, to be raised and lowered by said bar at the proper time and carried into engagement with the transverse reciprocating comb 27 or other device to be carried over the pile-wires 15 to form the pile-loops; but in 10 case of figured pile-fabric weaving there will be two or more sets of pile-warps, and all the pile-warps will be connected with a jacquard and the vertical movement of said warps will

be controlled by the jacquard; but the heddle-cords of all of said pile-warps will extend through holes in the vertically-moving lifting-bar 35 and will be provided with knots therein to be engaged by said bar. The raising of the lifting-bar 35 from the lower plane of the shed to the upper plane will carry with it to the upper plane all the pile-warps which have not been called and raised by the jacquard, and the further raising of the lifting-bar 35 to its highest position will carry with it above the upper ends of the blades 24, carrying the pile-wires 15, all the pile-warps 20 which have not been called and raised by the jacquard into engagement with the teeth 27' on the comb 27 to be carried over the pile-wires to form the pile-loops—that is, at regular intervals or after a certain number of picks, 25 preferably at every fourth pick, all the pile-warps which are not raised by the jacquard to their highest position are raised by the lifting-bar 35 or equivalent mechanism to their highest position or above the upper ends 30 of the blades 24, carrying the pile-wires 15. By this arrangement none of the pile-warps can remain down below the upper ends of the blades 24 for more than a certain number of picks, but must be raised to their highest position after a certain number of picks, and 35 consequently caused to be moved down on the proper side of the blades 24 in the formation of the shed and not interfere with the pile-warps which are moved across the pile-wires to form the pile-loops, thus preventing 40 to a great extent any imperfections in the weave of the fabric.

The lifting-bar 35 or equivalent mechanism is particularly intended to be used in connection with two or more sets of pile-warps operated from a jacquard.

It will be understood that the details of construction of my improvements may be varied, if desired.

Having thus described my invention, what I claim as new, and desire to secure by Letters Patent, is—

1. In a loom for weaving pile fabrics, the combination with two sets of upright blades of different lengths, and extending at their upper ends in two different horizontal planes, with the long and short blades arranged alternately, of pile-wires attached to the upright blades, and extending toward the front 115 of the loom, to form two sets of pile-wires in two different horizontal planes at their attached ends, substantially as shown and described.

2. In a loom for weaving pile fabrics, the 125 combination with two sets of upright blades extending in two different horizontal planes at their upper ends, of two sets of pile-wires attached to said blades, and extending toward the front of the loom and arranged in 130 two horizontal planes at their attached ends, substantially as shown and described.

3. In a loom for weaving pile fabrics, the combination with two sets of upright blades

extending in two different horizontal planes at their upper ends, of two sets of pile-wires extending toward the front of the loom and pivotally secured to said blades, and extending in two different horizontal planes at their attached ends, substantially as shown and described.

4. In a loom for weaving pile fabrics, the combination with a series of heddles, each 10 heddle having a bend or offset therein near its central portion, of blades attached to said heddles, with their upper ends substantially in line with said bends or offsets, and pile-wires attached to said blades and extending 15 out therefrom toward the front of the loom, substantially as shown and described.

5. In a loom for weaving pile fabrics, the combination with the heddles arranged in a single row, and each heddle having a bend or 20 offset therein near its central portion, of two sets of blades attached to said heddles, and having their upper ends extending in two different horizontal planes, and between the bends or offsets in said heddles, and pile-wires 25 secured to said blades and extending in two different horizontal planes at their attached ends, substantially as shown and described.

6. In a loom for weaving pile fabrics, the 30 combination with a heddle having an offset or bend therein at about its middle portion, of a pile-wire-supporting blade, secured at its lower end to said heddle, and a pile-wire having one end pivotally attached to the upper 35 end of said blade, substantially as shown and described.

7. In a loom for weaving pile fabrics, the combination with a heddle of flat metal having an offset or bend therein at about its middle portion, of a pile-wire-supporting blade 40 secured at its lower end to said heddle, and bent over at its upper end to form an eye or loop, substantially in line with the bend or offset in the heddle, and a pile-wire having one 45 end extending into said loop and attached therein, substantially as shown and described.

8. In a loom for weaving pile fabrics, the combination with a heddle of flat metal having an offset or bend therein at about its middle portion, of a pile-wire-supporting blade 50 secured at its lower end to said heddle and bent over at its upper end to form an eye or loop, substantially in line with the bend or offset in the heddle, and a pile-wire having one 55 end extending into said loop and attached therein, substantially as shown and described.

9. In a loom for weaving pile fabrics, the combination with two sets of upright blades of different lengths and extending at their 60 upper ends in two different horizontal planes, with the long and short blades arranged alternately, of pile-wires attached to the upright blades, and extending toward the front of the loom, to form two sets of pile-wires in 65 two different horizontal planes at their attached ends, and a device for moving the pile-

wires transversely across the pile-wires, substantially as shown and described.

10. In a loom for weaving pile fabrics, the combination with two sets of upright blades 70 extending in two different horizontal planes at their upper ends, of two sets of pile-wires attached to said blades, and extending toward the front of the loom, and arranged in two horizontal planes at their attached ends, 75 and a device for moving the pile-wires transversely across the pile-wires, substantially as shown and described.

11. In a loom for weaving pile fabrics, the combination with two sets of upright blades 80 extending in two different horizontal planes at their upper ends, of two sets of pile-wires extending toward the front of the loom and pivotally secured to said blades and extending 85 in two different horizontal planes at their attached ends, and a device for moving the pile-wires transversely across the pile-wires, substantially as shown and described.

12. In a loom for weaving pile fabrics, the combination with the heddles, each heddle 90 having a bend or offset therein near its central portion, and the blades attached to said heddles, and pile-wires attached to said blades, and extending out therefrom toward the front of the loom, of a device for moving 95 the pile-wires, transversely across the pile-wires, substantially as shown and described.

13. In a loom for weaving pile fabrics, the combination with the heddles, and the blades attached thereto, and the pile-wires attached 100 to said blades and extending toward the front of the loom, and heddles or cords for the pile-wires, and a device for moving the pile-wires transversely across the pile-wires, 105 of a vertically-moving bar or device connected with the heddles or cords of the pile-wires, and means for raising the same at regular intervals, or after a certain number of picks, to cause all the pile-wires which are not in their highest position to be carried up to their 110 highest position above the upper ends of the blades carrying the pile-wires, substantially as shown and described.

14. In a loom for weaving pile fabrics, the combination with the heddles, and the blades 115 attached thereto, and the pile-wires attached to said blades and extending toward the front of the loom, and heddles or cords for the pile-wires, and a device for moving the pile-wires transversely across the pile-wires, 120 of a vertically-moving bar, or device, connected with the heddles or cords of the pile-wires, and means for raising the same at regular intervals, or after a certain number of picks, to cause all the pile-wires which are not in their highest position to be carried up to their 125 highest position, substantially as shown and described.

15. In a loom for weaving pile fabrics, the combination with the heddles, and the blades 130 attached thereto, and the pile-wires attached to said blades and extending toward the

front of the loom, and heddles or cords for the pile-warps, and a device for moving the pile-warps transversely across the pile-wires, of a vertically-moving bar, or device, connected with the heddles or cords of the pile-warps, and means for raising the same, to cause all of the pile-warps which are down to be raised with said bar, substantially as shown and described.

JAMES BUCKLER.
